US00D917622S

(12) **United States Design Patent** (10) **Patent No.:** **US D917,622 S**
(45) **Date of Patent:** **** Apr. 27, 2021**

(54) **THUMBSTICK ATTACHMENT**

(71) Applicant: **Microsoft Corporation**, Redmond, WA (US)

(72) Inventors: **Elliott Hsu**, Seattle, WA (US); **Joshua P. Weiher**, Seattle, WA (US); **Dan Thorstenson**, Seattle, WA (US); **Jonathan Shea Robinson**, Seattle, WA (US); **Aaron Schmitz**, Seattle, WA (US); **Dustin Tiffany**, Woodinville, WA (US)

(73) Assignee: **Microsoft Corporation**, Redmond, WA (US)

(**) Term: **15 Years**

(21) Appl. No.: **29/690,803**

(22) Filed: **May 10, 2019**

(51) LOC (13) Cl. **21-01**

(52) U.S. Cl.

USPC **D21/333**

(57) **CLAIM**

The ornamental design for a thumbstick attachment, as shown and described.

DESCRIPTION

FIG. 1 is a top perspective view of a thumbstick attachment showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines shown in the drawings depict portions of the thumbstick attachment and form no part of the claimed design.

1 Claim, 5 Drawing Sheets
